CLAIM

The ornamental design for an automobile tire, as shown and described.

DESCRIPTION

FIG. 1 is a front elevation view of an automobile tire showing our new design, it being understood that the tread pattern is repeated uniformly throughout the circumference of the tire;

FIG. 2 is a side elevation view thereof, the opposite side being a mirror image of that one shown;

FIG. 3 is an enlarged fragmentary front elevation view thereof;

FIG. 4 is an enlarged sectional view thereof taken along line 4—4 of FIG. 3; and,

FIG. 5 is a perspective view thereof.

FIG. 1

FIG. 2

FIG. 3

FIG. 4

FIG. 5
